[57] CLAIM

The ornamental design for a drawing carrying case or similar article, as shown and described.

DESCRIPTION

FIG. 1 is a perspective view of a drawing carrying case or similar article showing our new design in a partially unfolded condition;

FIG. 2 is a perspective view looking down upon the top thereof in folded and partially-rolled condition;

FIG. 3 is an enlarged scale fragmentary perspective view of the upper rear edge showing the carrying handle, shoulder straps and roll-encircling straps; and,

FIG. 4 is a fragmentary perspective view showing one end thereof in rolled condition encircled by one of the roll-encircling straps and with the shoulder strap attached thereto.

The bottom of the case is plain except for the handle and straps shown in FIG. 3.
